Primary Examiner — Barbara Fox*Assistant Examiner* — Lilyana Bekic(74) *Attorney, Agent, or Firm* — Marshall, Gerstein & Borun LLP(57) **CLAIM**

The ornamental design for a breastshield for a breastpump, as shown and described.

DESCRIPTION

FIG. 1 is a first top perspective view of a breastshield for a breastpump of the present invention.

FIG. 2 is a second perspective view thereof;

FIG. 3 is a right side view thereof;

FIG. 4 is a left side view thereof;

FIG. 5 is a front view thereof;

FIG. 6 is a back view thereof;

FIG. 7 is a top view thereof; and,

FIG. 8 is a bottom view thereof.
